CARD INDEX AND SLIDABLE SIGNAL

Wilhelm F. Block, White Plains, N. Y., assignor
to Remington Rand Inc., New York, N. Y., a
corporation of Delaware

Application October 14, 1948, Serial No. 54,434

4 Claims. (Cl. 129—16.7)

1

This invention relates to improvements in visible index equipment and particularly to a slidable signal and card construction.

The invention provides an index card and signal for visible indexes having a slidable signal construction operable over a greater length of the visible margin of an index card for signaling information of a variable or progressive nature.

The invention provides a construction having a telescoping and sliding signal assembly associated with the visible indexed margin of a visible index card constructed so that a greater portion of the margin of the card, substantially more than half of the margin may be used for signaling purposes with the sliding and telescopic signal assembly. The telescoping sliding signal assembly is constructed so that a series of substantially duplicate signal sections may be arranged in overlapping interengaged relation and slidably retained by any suitable means on the visible margin of an index card. Substantially the entire signal assembly may be concealed from view at one limit of the operation of the signal which may be a non-signaling position, with the signal assembly arranged for progressive sliding movement over the visible card margin with each signal section being gradually extended with respect to its adjacent section until the extended signal assembly cooperates to cover the entire major portion of the card margin provided for signaling purposes. Suitable means for retaining the signals in interengaged relation against detachment from one another is provided by the invention and so arranged in cooperation with an index card that one of the signal sections of the telescoping assembly engaged through a slot in the index card is provided with means to interlock with a means on the index card to retain the signal assembly against complete detachment from the index card. Manual sliding of the signal assembly back and forth will bring as much of the signal assembly into visible relation on the margin of the card as may be desired for a desired signaling operation, while the remaining portion of the signal assembly is concealed behind another portion of the card or other suitable means associated therewith.

In the drawing:

Fig. 1 shows the lower portion of a card holder in elevation carrying an index card and a transparent marginal sheath with a plurality of interengaged signals in extended signaling relation over the visible card margin, a portion of the sheath being removed for clarity in illustration.

Fig. 2 is a fragmentary elevation of the lower

2

portion of the card holder and index card shown in Fig. 1, showing how a plurality of individual signals are held in telescoped, abutting and non-signaling relation when not in use.

Fig. 3 is a longitudinal cross-section taken substantially on line 3—3 of Fig. 1, illustrating the interengagement of the cooperative means of the contiguous telescoping signals.

Fig. 4 is a vertical cross-section, taken substantially on line 4—4 of Fig. 1.

Fig. 5 shows the telescoping signals shown in Fig. 1, in perspective.

Fig. 6 is a fragmentary elevation of the lower portion of a card holder and index card similar to the one shown in Fig. 1, showing a modified form of telescoping signal provided with means for interengaging an index card in a manner different from that illustrated in Fig. 1.

Fig. 7 shows one of the signals shown in Fig. 6, in perspective.

Fig. 8 shows a signal arranged for sliding interengagement with another signal in perspective, but without means for interlocking engagement with the index card or a contiguous telescoping signal.

A card holder 10 is provided with a transparent sheath 11 along one margin, said sheath being secured thereon in any suitable manner well-known in the art, as by wire stitches 12. The other marginal end of card 10 is provided with means (not shown) for hingedly mounting said card holder on a panel or tray in visible indexed relation with other similar card holders in a manner well-known in the art. Other well-known means, such as diagonal slots, are provided adjacent the marginal corners of the portion of card holder 10, not shown in the drawing, for removably securing one margin of a record card 13 adjacent the means for suspending the card holder on a panel or tray. Data of any kind may be recorded on the card and is usually arranged in rows and columns. An index is provided along the other and visible margin 14 of record card 13, said margin 14 being engaged in and enclosed by sheath 11.

The front upper edge of sheath 11 has inturned flange 15 extending across visible margin 14 when card 13 is engaged in the sheath and supported on the card holder. Visible margin 14 of record card 13 is provided with a slot 16 extending transversely thereof and located near the left-hand edge of card 13, as shown in the drawing. An aperture 17 is formed in card 13 adjacent slot 16 and located between slot 16 and the left-hand edge of card 13. Slot 16 and aperture 17 are

enclosed in sheath 11 when margin 14 is engaged in the sheath and supported on the card holder.

Slot 16, as illustrated, is positioned at a distance from the left-hand edge of margin 14 equal to about one-fourth of the length of the visible margin. This enables the major length of the visible margin to be indexed for visible signaling purposes while the shorter left-hand portion of margin 14 may receive the visible index for the card and the information recorded thereon. A telescoping signal assembly is indicated at 18 for cooperation with index indicia 38 on margin 14 for signaling purposes. Signal assembly 18 is formed of a plurality of transparent flexible strips 19. Each signal section 19 has an elongated body portion slightly greater in length than one-quarter of the length of margin 14 of record card 13, as shown in the drawing. The length of the body portion of each section 19 is determined for any telescoping signal assembly made according to the invention by the distance between slot 16 and the adjacent edge of card 13 behind which the signal assembly is concealed in its fully telescoped position. A handle 20 extends laterally at one end of each section 19 and projects outwardly over card 13 beyond the upper edge of sheath 11 for manual engagement so the signal may be adjusted. The end of each section 19 formed with handle 20 also has a diagonal slot 21 formed therein in transverse inclined relation and opening outwardly at the lower edge. Each section 19 is cut away at 22, to provide a beveled corner to facilitate insertion of signal section 19 in slot 21 of an adjacent signal section and in slot 16 of index card 13.

A plurality of struck-out or offset lips or blisters are formed in each section 19 for slidably engaging under inturned flange 15, slidably retaining signal assembly 18 in sheath 11 and also, for interengagement of lips on one signal with lips on the next adjacent signal in providing for the desired operation of the signal assembly. In the form shown in Figs. 1 to 5, lips 23 and 24 are located at the handle end of each section 19 and arranged in vertical alignment below handle 20. Lip 23 projects forwardly from the body portion of each section 19 and forms a horizontally disposed shoulder slidably engaged against the lower margin of returned flange 15 to prevent vertical displacement of each section 19 and signal assembly 18 relative to sheath 11. Lip 24 projects rearwardly from the body portion of each section 19 in the central portion of the handle end, forms a vertically arranged shoulder facing the opposite end of the section and is in horizontal alignment with lip 25 projecting forwardly from the opposite end of each section 19.

Lips 24 and 25 provide shoulders arranged in opposed relation for engagement with one another when one section 19 is pulled to the right as shown in Fig. 1 into an extended position with respect to the next adjacent section 19 for pulling this adjacent section with it toward extended relation in further sliding movement of inner right-hand section 19 toward the right-hand side of card 13. Lips 24 and 25 on adjacent sections 19 cooperate to retain one section engaged in slot 21 in an adjacent section against detachment so that a series of sections 19 may be interengaged for relative sliding or telescoping movement between an overlapping telescoped position, as shown in Fig. 2, or an extended position as shown in Fig. 1. Lip 25 on the foremost signal engages in aperture 17 when a series of signal sections 19 of assembly 18 are in extended relation as shown

in Fig. 1, thus providing an anchor to limit the movement of the assembled signals in extended relation by preventing withdrawal of said foremost section 19 from engagement in slot 16.

5 The indicia 38 on margin 14 of card 13 may be printed on the margin of the card between slot 16 and the right-hand edge of the card as shown in the drawing, to indicate any desired scale or type of information that may be useful in signaling information of a desired character, recorded in connection with the data on the card that is customary in the use of visible index signals.

10 It is to be understood that in referring to index card 13 and margin 14 as a means of providing a structure having a slot 16 for concealing a portion of the signal assembly 18 and having another portion exposed over the margin 14 for cooperation with scale or indicia 38, the invention further contemplates the use of a separate strip or 15 insert, generally known in the art as a title insert, over the face of the card which functions in exactly the same manner as the card in the above description. It is well-known that a title insert 20 may be provided with a slot 16 and provide the visible marginal portion 14 within sheath 11 exposed to view in a visible index over the marginal portion of an index card carried in the card holder. The title insert or index strip is supported 25 by sheath 11 and the card holder with an index card in a well-known manner. Reference to a 30 visible margin or the like for cooperation with the signal assembly in the claims will be understood to include a title insert or similar strip 35 as well as index card 13.

Signal section 26, Fig. 7, is generally similar to signal section 19 of signal assembly 18. It has body 27, handle 28 at one end, diagonal slot 29, beveled corner 30, and retaining lip 31. All of 40 these parts of section 26 have the same length, shape, and location as the corresponding elements 19, 20, 21, 22 and 23 respectively, of signal section 19, and perform similar functions in a similar manner. Lips similar to lips 24 and 25 45 of signal sections 19 are omitted. Instead, a projection 32 is formed on the upper edge of signal 26 at the end opposite handle 28 to engage card 13 adjacent slot 16 or the handle end of an adjacent signal section 26 to retain the signal sections against disengagement from card 13 and from each other. The manner in which projection 32 on one signal section 26 interengages with an adjacent signal section and card 13 is clearly 50 shown in Fig. 6. Otherwise, the use and operation of section 26 and a signal assembly using 55 sections 26 is the same as described in relation to signal assembly 18.

Signal section 33, Fig. 8, is generally similar in shape and size to signal sections 19 and 26. It has body 34, handle 35, diagonal slot 36, beveled 60 corner 37, and is of similar shape, size, and location as the corresponding parts 19, 20, 21 and 22 respectively, of signal section 19. Signal sections 33 may be assembled and operated with an index card in substantially the same manner as signal assembly 18. All interlocking elements, 65 however, are omitted. Signal sections 33 may be moved freely in and out of sheath 11 independently of one another but also in telescoping relation relative to each other to obtain the same signaling cooperation with an index card margin as signal assembly 18. It is particularly adapted for use when additional or supplemental signals 70 are required in addition to a series of signal sec-

tions 19 or 26, as shown in Figs. 1 and 3, respectively.

Signal sections 19, 26, and 33 will generally be made up of substantially transparent material contrasting in color with record card 13, and when used in a series of signals, the various individual signals may optionally be all of one color or of a variety of different colors.

In a visible index using a signal assembly with an index card, insert or the like on a card holder having an indexed marginal portion arranged to cover the major portion of the width of the card, card holder, or the like, it will be understood that the signal assembly provides for the telescoping of a plurality of signal sections into overlapping relation as illustrated in the drawing in Fig. 2 in concealed relation behind a margin of the index card or insert with the handles on the signals in position for manual engagement so that one or more signals may be moved over the visible portion of the index card margin for signaling purposes. By using telescoping signals it will be clear that when the signals are in telescoped relation a plurality of sections sufficient to cover the entire width of the card margin can be provided. They may be concealed behind a relatively small portion of the card margin, substantially less than half of the margin in telescoped relation. This leaves the major portion of the card margin substantially more than half, such as three-quarters of the card margin, as shown in the drawing, exposed to view for indexing purposes with the use of the telescoping signal assembly for signaling cooperation with indicia 38 applied to the major portion of the card margin to the right of slot 16. In this way, the telescoping signal assembly facilitates an indexing and signaling operation in a visible index with each card and card holder having a major portion, considerably more than half of the visible margin of a card used for the signaling operation, thereby obtaining a substantially improved indexing and signaling system employing the telescoping signal assembly.

Sheath 11 cooperates with index card 13 and the several signal sections when constructed as shown for example in Figs. 6, 7 and 8, to retain the assembled sections in telescoping relation with one end portion slidably engaged through the slot in the opposite end of an adjacent signal such as slot 21. In turn flange 15 cooperates with retaining projections 23 or 31 to slidably hold the signal sections on the card holder in cooperation with the portion of the card at the upper end of slot 16 for normally preventing their accidental detachment from the card holder and sheath. With signals constructed, as shown in Figs. 6 and 7, the sections may be advantageously interengaged through slot 16 in the card and through slots 21 or 29 of an adjacent signal section for interengaging two or more signal sections in slidable relation for telescoping operation. Projections 24 and 25 on adjacent signal sections 19 cooperate for retaining a pair of adjacent signal sections from being disengaged from one another when one signal section is moved into an extended relation with respect to an adjacent interengaged signal section. These projections or lips also cooperate to transmit the motion applied to the handle of one signal section to secure movement of all of the trailing signal sections associated therewith in telescoping relation. In this way an end signal section of an assembly 18 may be moved to the right from the position shown in Fig. 2 to that shown

in Fig. 1, by manually engaging an operating handle 20 at the right-hand side of the signal assembly, as shown in Figs. 1 and 2. By moving the end signal at the right-hand end of the assembly, as shown in the drawing, to the right from the position shown in Fig. 2 to that shown in Fig. 1, projections 24 and 25 will cooperate to pull the trailing sections 19 into the position shown in Fig. 1 without manually engaging handles 20 of the two sections shown to the left of the right-hand section 19. Projection 25 on the foremost signal at the left-hand side of the signal sections 19 shown in Fig. 1 also cooperates with card 13 through aperture 17 to limit the movement of signal assembly 18 in the extended position relative to card 13 for normally retaining the signal sections against detachment from card 13 through slot 16.

Projection 32 on each signal section 26 secures an operation similar to projections 24 and 25 by cooperating with card 13 above the end of slot 16 to retain one signal of a signal assembly at one end thereof against detachment from the index card through slot 16. On the other interengaged signals of an assembly, projections 32 will cooperate with the opposite end adjacent handle portions 28 for retaining adjacent signals against complete detachment from one another by withdrawal of the signals through slots 29 in a manner clearly shown in Fig. 6.

Beveled ends 22, 30 and 37 of the several signal sections facilitate the insertion of each signal section into assembled relation with a card and card holder in sheath 11. These beveled ends facilitate the insertion of the end of a signal section through slot 21, 29 or 36 respectively of an adjacent signal as well as slot 16 in an index card.

A plurality of signal sections 33 may be used to provide a signal assembly in telescoped relation with one end of each signal section 33 engaged through slot 36 of an adjacent signal section with the signal sections arranged for the engagement of the ends thereof through slot 16 in an index card for relative telescoping movement. Since no projections are provided on signal sections 33 for interengagement with cooperating complementary projections on an adjacent signal, it is obviously necessary in operating a signal assembly using signal sections 33 to move each section independently of the other by manually engaging each handle 35. A plurality of signal sections 33 may be operated so as to secure the complete cooperation with indicia 38 that is secured by the construction shown in Figs. 1 and 2, through the relative operation of each signal section manually relatively to one another into an extended relation, such as shown in Fig. 1.

The invention claimed is:

1. An index device comprising a card having a slot in one edge portion, a signal slidably mounted for signaling cooperation with a margin of said index card having one end adapted to extend through said slot, means on said signal adjacent said one end to engage said index card and retain said signal against complete detachment from said card, said signal having a slot formed at its other end, a second signal slidably engaged in the slot of said first-mentioned signal, means on said second signal at one end for engaging and retaining said second signal against complete detachment from said first signal, said signals being movable between overlapping telescoped relation and an extended rela-

tion in signaling cooperation with said margin of said card.

2. An index device comprising an index card having a slot formed in one margin about one-fourth the distance from one end of said margin, a sheath of transparent material embracing said margin of said card, and a plurality of signal strips slidably mounted in telescopic relation in said sheath for signaling cooperation with said card margin, each signal strip having a length substantially equal to about one-fourth the length of the margin of said card, each signal strip having a slot formed in one end slidably receiving a contiguous signal strip in overlapping interengaged telescoping relation for sliding movement relative to said index card and other signal strips, said interengaged signal strips extending through said slot in said index card in superimposed relation and having portions exposed and portions concealed by said card margin, said exposed signal portions being variable for variable signaling cooperation with said card margin, a handle on each signal strip adjacent said slot means for manual engagement to move each signal strip relative to said index card and to each other, and stop means on the opposite end of each signal strip to limit the sliding movement of said signal strips relative to said card and to each other.

3. The structure of claim 1 in which a second stop means is provided adjacent each handle, said second stop means cooperating with a portion of said sheath to retain said signal strips in said sheath.

4. A signal for visible indexes comprising an elongated strip, an extension on one end projecting laterally from one side and forming a handle, said strip being formed with a transverse slot adjacent said handle opening through the opposite side for slidably receiving another signal, a retaining projection integrally formed on the opposite end of said strip for cooperation with a similar signal when said opposite end is engaged through the slot of said similar signal to retain two signals slidably interengaged against complete detachment from one another.
